COMBINATION FORK, SPOON, AND KNIFE

Arthur L. Kuhlman 38192 Murdock Drive,
New Baltimore, Mich.

Filed Mar. 23, 1960, Ser. No. 59,842

Term of patent 14 years

(Cl. D54—12)

Fig. 2

Fig. 1

Fig. 4

Fig. 5

Fig. 1 is a side elevational view of a combination fork, spoon and knife showing my new design.

Fig. 2 is a plan view thereof.

Fig. 3 is a transverse sectional view taken on line 3—3 of Fig. 2.

Fig. 4 is also a transverse sectional view taken on the line 4—4 of Fig. 2.

I claim:

The ornamental design for a combination fork, spoon and knife, as shown.
